UNITED STATES PATENT OFFICE.

ALFRED WARD, OF PORT HURON, MICHIGAN.

BLACKING-BOX CASE.

1,074,914.

Specification of Letters Patent.

Patented Oct. 7, 1913.

Application filed November 18, 1912. Serial No. 732,154.

To all whom it may concern:

Be it known that I, ALFRED WARD, a citizen of the United States, residing at Port Huron, in the county of St. Clair and State 5 of Michigan, have invented certain new and useful Improvements in Blacking-Box Cases; and I do declare the following to be a full, clear, and exact description of the invention, such as will enable others skilled 10 in the art to which it appertains to make and use the same.

This invention relates to improvements in blacking box cases and in the present embodiment is shown as a holder for shoe polish and as having in connection therewith a 15 dauber and a polisher.

One object of the invention is to provide a blacking box case of this character having an improved construction and arrangement 20 of polish box support provided with a box engaging cover which opens and closes automatically when the support is drawn out of and pushed back into the holder.

Another object is to provide a blacking 25 box case which is adapted to serve as a back and handle for the polisher carried thereby.

With these and other objects in view, the invention consists of certain novel features of construction, and the combination and arrangement of parts as will be more fully described and claimed.

In the accompanying drawings; Figure 1 is a perspective view of my improved polish 35 holder; Fig. 2 is a vertical longitudinal sectional view through one side of the holder taken on the line 2—2 of Fig. 5; Fig. 3 is a central vertical longitudinal section of the holder with the polishing box support in a projected or operative position and the automatically operated box cover open; Fig. 40 Fig. 4 is a plan view of the inner portion of the body of the holder with the top or outer section thereof removed; Fig. 5 is a vertical cross sectional view taken on the line 6—6 45 of Fig. 2.

My improved blacking box case comprises a body which may be of any suitable size and shape and which preferably consists of an inner section 1 and an outer or top section 2 which is secured to the inner section 50 in any suitable manner. The inner sides of the inner and outer sections 1 and 2 of the body of the casing are recessed for a suitable distance at one end of the holder to 55 form a compartment 3 adapted to receive

the polish box support 4 and polish box 5 carried thereby.

The polish box support 4 comprises a shallow tray which is here shown and preferably conforms to the shape of the end of 60 the body with which the tray is engaged. The tray is secured at its inner end in any suitable manner to inwardly extending guiding and supporting rods 6 which are slidably engaged with guide passages 7 in the 65 body 1 adjacent to the sides thereof as shown. On the outer end of the tray 4 is preferably secured a flexible tab 8 by means of which the tray or the box support may be readily drawn out of the compartment 3 70 and pushed back therein. In the bottom of the tray is formed an aperture 9 and cut and struck up from the bottom of the tray near its inner end are upwardly projecting box 75 engaging lugs 10 between which and the flange or side of the tray is secured the 80 polish box 5. The lugs 10 are preferably arranged in such positions with respect to the flange or side of the tray as to firmly hold the polish box in place. When it is desired 85 to remove the empty polish box from the support the same may be pushed out from the bottom of the tray by engaging the box through the opening 9 in the bottom of the tray as will be readily understood.

Hinged at its inner edge to the inner end 90 of the tray or support 4 is a box cover 11 which is preferably in the form of a flat plate corresponding in shape and size to the tray and is adapted to swing down into engagement with the upper edge of the 95 polish box carried by the tray. Arranged on the outer side of the cover 11 near its side edges and a suitable distance from its pivotally connected inner end are eyes 12 with which are loosely connected the outer ends of cover opening rods 13 which extend back through passages 14 in the upper section of the body of the holder and are slidably engaged with combined guiding eyes and stops 100 15 which are secured in the lower section of the body and are disposed at suitable positions in the passages 14. On the inner ends of the rods 13 are knobs 16 which when the tray or support 4 is drawn out of the compartment 3 will engage the eye 15 which will prevent further outward movement of the rods, so that on the continued outward movement of the tray or support the rods 105 will pull upon and swing the cover 11 up- 110

wardly and rearwardly to an open position as clearly shown in Fig. 4 of the drawings thereby uncovering the tray and the box of polish carried thereby.

5 When sufficient polish has been removed from the box the tray or support 4 is pushed back into the compartment 3 which movement of the tray will bring the cover 11 into engagement with the outer edge of the 10 upper portion of the compartment 3, so that said edge will swing the cover back down upon the box thereby closing the same and permitting the tray, box and the cover to be pushed entirely back into the compartment 3 as clearly shown in Figs. 2 and 15 5 of the drawing. By thus constructing and arranging the supporting tray for the box of polish and the top or cover 11, the latter will be automatically opened and closed when the tray is drawn outwardly or pushed back into the body of the holder.

In the present embodiment of this invention, the sections 1 and 2 are shown as having openings 17 and 18 which are adapted 25 to form a receptacle for the head and handle of the dauber 19. A cover 20 closes these openings. To the lower surface of section 1 is secured a polisher 21, thus combining in a single compact article the three 30 elements, the dauber, the blacking box and the polisher.

From the foregoing description taken in connection with the accompanying drawings, the construction and operation of the 35 invention will be readily understood without requiring a more extended explanation.

Various changes in the form, proportion and the minor details of construction may be resorted to without departing from the 40 principle or sacrificing any of the advantages of the invention as shown.

Having thus described my invention, what I claim is:

1. A blacking box case comprising a body 45 having in one end a compartment, a polish box supporting tray removably engaged with said compartment, tray supporting rods having a sliding engagement with said body whereby the tray is supported in an 50 operative position when drawn from said compartment, a cover hingedly connected with said tray, and means whereby the cover

is automatically swung to open and closed positions when the tray is drawn out and pushed back into said compartment. 55

2. A blacking box case comprising a body having in one end a compartment, a polish box supporting tray removably engaged with said compartment, means to support the tray when withdrawn from said compartment, a cover plate hinged to said tray, cover opening rods slidably mounted in said body and having a loose connection at their outer ends with said cover, knobs carried by the inner ends of said rods and combined guide members and stops to receive and guide said rods and to form stops with which the knobs on the ends of the rods are engaged when the tray is drawn out of the compartment whereby the rods will swing 70 the cover upwardly to an open position, said cover being closed by the engagement therewith with the end of the body when the tray is pushed back into said compartment.

3. A device of the character set forth 75 comprising a body having a compartment with an open end, a tray to slide into and out of the compartment, a cover for the tray, and means actuated by the movement of the tray to lift the cover therefrom when it is 80 drawn out of the compartment.

4. A device of the character set forth comprising a body having a compartment with an open end, a tray to slide into and out of the compartment, a cover hinged to 85 the tray and means actuated by the movement of the tray, whereby the cover will be lifted when the tray is drawn out of the compartment.

5. A device of the character set forth 90 comprising a body having a compartment with an open end, a tray to slide into and out of the compartment, a cover hinged to the tray, and actuating rods for the cover connected at one end to it adjacent its hinge, 95 the opposite ends of the rod being connected to the body.

In testimony whereof I have hereunto set my hand in presence of two subscribing witnesses.

ALFRED WARD.
